UNITED STATES PATENT OFFICE.

ROY DONALD SPRINGER, OF GRESHAM, OREGON.

IRONING TABLE.

Application filed November 3, 1921. Serial No. 512,446.

To all whom it may concern:

Be it known that I, ROY DONALD SPRINGER, a citizen of the United States, and a resident of Gresham, county of Gresham, and 5 State of Oregon, have invented a certain new and useful Improvement in Ironing Tables, of which the following is a specification.

The object of my invention is to provide 10 a folding ironing table of simple construction which folds in a compact form and is adapted to support the ironing board firmly when extended in a horizontal position. My invention further has for its object to make 15 my improved ironing board of strong construction throughout.

I attain my object by the device comprising the following elements illustrated in the accompanying drawings, in which:

20 Fig. 1 is a perspective view showing the ironing table in an extended horizontal position so that the table is arranged for ironing;

Fig. 2 is a bottom view showing the table 25 collapsed and folded showing how all of the parts are spaced so that when they are folded they form a compact body;

Fig. 3 is a cross sectional view taken on the line 3—3 of Fig. 2; this shows the manner of folding the ironing table and how the 30 parts fold in relation to each other.

In my drawings I have shown the ironing board *a* which is supported by two legs which are attached to the broad end of the 35 board. One leg comprises uprights *b* spaced apart and braced by the cross members *c*, *c'* and *c''*, and the other leg is in the form of a crutch and braced across by one member *g'*.

40 These legs are connected to the cleats *m* on the board *a* by a rod *i* on which they hinge. The board is held in a horizontal position by a strut *e* which is attached to a link *d* which in turn is attached to the bot-

tom cross-member *c* by two staples *l*. This 45 link *d* pivots in two points, on one end through the staples *l* and on the other end where it is attached to the strut *e*. This strut *e* is supported on its under side by the brace bar *f* to which it is fastened by 50 the hinge *k* and when the ironing table is in its extended position the brace bar *f* is removably engaged in the crutch *g* by being positioned against the lower end *h* of the crutch *g*. To knock down the ironing table 55 the brace bar *f* is removed from its position against the lower end *h* of the crutch *g* and the pressure against the board *a* is thereby released from strut *e*. This will allow the strut *e* to pivot on the rod *j* and the link *b* 60 will pivot as shown in Fig. 3. As all of the legs and the board are pivoted on the rod *i* these can all be swung closed as shown in Fig. 3 so that the folded board will appear like the sketch shown as Fig. 2. 65

The illustrations and description above given are merely intended to show a practical mode of construction of my device. The particular details of construction above described are, however, variable to suit the 70 ideas of the manufacturer; provided such variation retains the essential features of my invention.

I claim:

An ironing table comprising a leg, an 75 ironing board hinged at one end to the upper end of said leg, a crutch hinged at its upper end to said board, comprising spaced members, a strut hinged between the members of said crutch, a brace bar the upper 80 end of which is hinged to said strut, the lower end of said bar being releaseably engageable with the lower end of said crutch and when so engaged supporting the ironing board in horizontal position, and a link 85 connecting the lower end of said strut with the base of said leg.

ROY DONALD SPRINGER.
